Attorney

UNITED STATES PATENT OFFICE.

ALBERT B. CALLOWAY, OF ACKERMAN, MISSISSIPPI.

BEDSTEAD ATTACHMENT.

1,360,985.

Specification of Letters Patent. Patented Nov. 30, 1920.

Application filed February 20, 1920. Serial No. 360,223.

To all whom it may concern:

Be it known that I, ALBERT B. CALLOWAY, a citizen of the United States, residing at Ackerman, in the county of Choctaw and 5 State of Mississippi, have invented certain new and useful Improvements in Bedstead Attachments; and I do hereby declare the following to be a full, clear, and exact description of the invention, such as will enable others skilled in the art to which it appertains to make and use the same.

This invention relates to bedsteads and the primary object of the invention is to provide an improved means for attaching 15 the side rails or pieces to the head and foot sections of a bedstead.

Another object of the invention is to provide a means for locking the side rails in engagement with the head and foot pieces so as 20 to prevent accidental displacement thereof.

A further object of the invention is to provide an improved means for quickly and efficiently connecting the side rails to the head and foot pieces of a bed so as to 25 permit the convenient and quick assembling thereof.

A still further object of the invention is to provide an improved device of the above character, which is durable and efficient in 30 use, one that is simple and easy to manufacture, and one which can be placed upon the market at a reasonable cost.

With these and other objects in view, the invention consists in the novel construction, 35 arrangement and formation of parts, as will be hereinafter more specifically described, claimed and illustrated in the accompanying drawings, forming a part thereof in which—

Figure 1 is a fragmentary side elevation 40 of a bedstead showing the improved device applied thereto,

Fig. 2 is a detail perspective view of the device removed from the bedstead,

Fig. 3 is a detail horizontal section taken 45 on the line 3—3 of Fig. 1.

Referring to the drawings in detail, wherein similar reference characters designate corresponding parts throughout the several views, the numeral 1 generally indicates the attachment, which is adapted to be secured to the head 2 of a bedstead 3. While the device has only been shown used in connection with the head piece, it is to be understood that it is to be used for the foot 50 piece as well. The device 1 includes a metallic casing 4 having a side wall 5, an

end wall 6 and top and bottom walls 7 and 8 formed thereon. The housing as shown is preferably formed of a single sheet of metal and the upper and lower walls 7 and 8 have 60 formed on the inner ends thereof outwardly extending attaching ears 9, which are apertured for the reception of suitable fastening elements whereby the device may be readily secured to the inner surface of the 65 head piece. The upper and lower walls 7 and 8 form flanges for the reception of the side rail 10 forming a part of the bedstead. Right angularly positioned inwardly extending guide flanges 11 and 12 are formed 70 on the upper and lower walls respectively and form means for preventing the accidental lateral movement of the side rail in relation to the head and foot pieces.

The retaining flange 11 is substantially 75 triangular in configuration and the lower end thereof is provided with a pair of spaced apertured lugs 13, which are adapted to be embraced by the apertured ears 14 of the operating lever 15. A suitable pivot pin 80 16 extends through the alined openings formed in the ears 14 and the lugs 13 and forms means whereby the lever may be readily swung on the ears. The lever 15 forms a cam and the inner surfaces of the 85 ears 14 thereof are sharpened as at 17 for biting into the side rails 10 so as to prevent displacement thereof and the side rails 10 are provided with vertically extending spaced grooves 18 for the reception of said 90 ears.

In operation of the improved device the side rails 10 are slid in the housing 4 while the cam lever is in its raised position which positions the sharpened end 17 thereof outward of the retaining flanges and after the end piece is in position, the lever 15 is swung downwardly which will throw the inner sharpened edges of the ears 14 into the grooves and thus effectively lock the same 100 in position against movement.

In practice, I have found that the form of my invention, illustrated in the accompanying drawings and referred to in the above description, as the preferred embodiment, is the most efficient and practical; yet realizing the conditions concurrent with the adoption of my device will necessarily vary, I desire to emphasize the fact that various minor changes in details of construction, proportion and arrangement of parts may be resorted to, when required 105 110

without sacrificing any of the advantages of my invention as set forth.

What is claimed is:—

In a device of the class described the combination with a bedstead including head and foot pieces, and side rails, of a housing secured to the inner surface of the head and foot pieces formed from a single blank including a side wall, upper and lower walls 5 formed on the side wall, a rear wall formed on the side wall, outwardly extending ears formed on the upper and lower walls, said ears and rear wall having openings formed

therein for the reception of fastening elements, retaining flanges carried by the upper and lower walls and a cam lever carried by one of said retaining flanges and adapted to be brought into and out of engagement with the side rails, as and for the purpose specified.

In testimony whereof I affix my signature in presence of two witnesses.

ALBERT B. CALLOWAY.
